UNITED STATES PATENT OFFICE.

GEORGE H. GARCELON, OF SWISSVALE, AND JOSEPH L. CHANTEMERLE, OF TURTLE CREEK, PENNSYLVANIA, ASSIGNEES TO WESTINGHOUSE ELECTRIC AND MANUFACTURING COMPANY, A CORPORATION OF PENNSYLVANIA.

CENTRIFUGALLY-ACTUATED SHORT-CIRCUITING DEVICE.

1,425,639.

Specification of Letters Patent. Patented Aug. 15, 1922.

Application filed May 3, 1916. Serial No. 95,028.

To all whom it may concern:

Be it known that we, GEORGE H. GARCELON, a citizen of the United States, and a resident of Swissvale, in the county of Allegheny and State of Pennsylvania, and JOSEPH L. CHANTEMERLE, a citizen of the United States, and a resident of Turtle Creek, in the county of Allegheny and State of Pennsylvania, have invented a new and useful Improvement in Centrifugally-Actuated Short-Circuiting Devices, of which the following is a specification.

Our invention relates to centrifugally actuated short-circuiting devices for dynamo-electric machines, and it has particular relation to single-phase motors of the commutator type that are adapted for repulsion operation during the starting period and for induction operation after a predetermined speed has been attained.

The object of our invention is to provide a simple and effective device for short-circuiting the commutator of such a motor that is automatically controlled by a device which is responsive to variations in the speed of the motor.

Short-circuiting devices of the above-mentioned type, as heretofore constructed, have usually comprised a sleeve slidably mounted on the motor shaft and adapted to be moved longitudinally of the shaft by centrifugally-actuated levers. The short-circuiting device has usually been maintained out of engagement with the commutator cylinder by a spring and has been so constructed that, as the device was moved into engagement with the commutator cylinder, centrifugal force caused an outward radial movement of pivotally mounted contact elements, thereby maintaining good electrical contact between the short-circuiting device and the surface of the commutator cylinder. In order to utilize the effect of centrifugal force on the contact elements, it was necessary to provide

a commutator cylinder of special construction so that contact could be made with the inner peripheral surface of the segments of the commutator cylinder. This special construction of the commutator cylinder and the necessity of providing contact elements that were capable of being actuated by centrifugal force, have proven to be serious obstacles in attempting to simplify the con-

struction and to reduce the cost of single-phase motors of the commutator type. 55

According to the present invention, we provide a novel form of short-circuiting device that is capable of both rotative and axial movement with respect to the motor shaft and commutator cylinder so that contact can readily be made with the end surface of a commutator cylinder of the usual construction.

In the accompanying drawing, Fig. 1 is a view of a portion of a motor provided with a short-circuiting device constructed in accordance with our invention; Fig. 2 is a detail end view of the short-circuiting device shown in Fig. 1; Fig. 3 is a view, partially in section and partially in side elevation, 70 of the short-circuiting device; Figs. 4, 5 and 6 are detail views, showing various parts of the device, and Figs. 7 and 8 are detail views showing modifications in the form of the contact plate. 75

The motor comprises a stationary magnetizable member 1 provided with a winding 2 and an armature structure 3 carried on a shaft 4 that is rotatably mounted in bearings 5, only one of which is shown. The bearing 5 is carried by an end-bracket 6 which also supports brush-holding devices 7 that are adapted to coact with a commutator cylinder 8 forming a part of the armature structure 3. 85

As best shown in Figs. 2 and 3, the short-circuiting device comprises an annular plate 9 that is movably mounted on an extension 10 of the spider 11 of the commutator cylinder 8. The extension 10 is provided with a helical groove 12 within which is located a pin 13 that projects from the inner peripheral surface of the plate 9. A governor support 14, preferably formed as shown in Fig. 4, comprises a hub portion 15 that is adapted to be secured to the shaft 4 by means of a set screw 16, and oppositely disposed lugs 17 that are respectively provided with a central aperture 18. Governor arms 19, as best shown in Fig. 5, respectively comprise crescent shaped plates 20 between which is secured a curved weight 21 by means of a rivet 22 and a pin 23. The pin 23 is provided, at one end, with an enlarged portion 24 and is riveted over at its other end against the surface of the left-

hand plate 20. The weight 21 occupies only a portion of the space between the plates 20 so that their respective end-portions 25 are spaced apart and are adapted to embrace the 5 lugs 17 of the support 14. The arms 19 are pivotally mounted on the support 14 by means of pins 26 extending through the end portions 25 and the apertures 18 of the lugs 17. The arms 19 are held in a retracted 10 position with respect to the shaft 4 by means of springs 27 respectively secured, at their ends, between projections 28 provided on the support 14 and ears 29 provided on one of each pair of plates 20. The plate 9 is provided with diametrically arranged slots 30 within which project the enlarged portions 24 of the pins 23 carried by the governor arms 19. The plate 9 carries an annular contact plate 31 of substantially the same outer 15 side diameter as the commutator cylinder 8. The contact plate 31 is provided with radial slots 32, thereby forming fingers 33 that are slightly inclined with respect to the body portion of the plate 31, as best shown in Fig. 3. Each finger 33 is provided at its end, 20 with a curved portion 34. The contact plate 31 is also provided with slots 35 that are adapted to register with the slots 30.

Having fully described the various parts 30 embodied in the invention, the operation of the device is as follows. When the motor is at rest, the springs 27 hold the governor arms 19 in a retracted position, and the pins 24, coacting with the slots 30, maintain the 35 plate 9 in its extreme left-hand position, as shown in Fig. 3. The motor is then adapted to start as a repulsion motor. As the motor accelerates, the governor arms 19 tend to move outwardly about their pivots under the 40 influence of centrifugal force. The springs 27 are so connected to the arms 19 that the moment arms through which the springs act, decrease as the governor arms move outwardly, so that movement of the arms to 45 their extreme outward positions is accomplished quickly when the motor reaches a predetermined speed. As the governor arms move outwardly, the pins 24, sliding in the slots 30, cause the plate 9 to rotate in a 50 clockwise direction. The plate 9 being movably mounted on the portion 10 and the pin 13 being slidable within the helical groove 12, it is apparent that any rotative movement of the plate 9 will result in its simultaneous axial movement towards the commutator cylinder 8. The helical groove 12 is so proportioned that the curved portions 34 of the fingers 33 will make contact with the end surface of the commutator cylinder 8 before the pin 13 reaches the end of its travel in the groove 12. The initial contact 60 of the plate 31 with the commutator cylinder will be made by a wiping movement of the curved portions 34 in both a radial and a rotative direction. It is apparent that good

electrical contact will be maintained between portions 34 of the fingers 33 and the commutator cylinder 8, so long as the governor arms are in their extended positions, by reason of the fact that the somewhat resilient 70 contact fingers 33 are distorted from their original form when the plate 9 is in its extreme right-hand position.

While the fingers of the plate 31 are in contact with the commutator cylinder 8, the 75 segments of the commutator cylinder 8 will be short-circuited and the motor will operate as an induction motor. If, however, for any reason, the motor falls below its normal operating speed, the springs 27 will retract 80 the governor arms 19 and cause them to withdraw the contact plate 31 from the surface of the commutator cylinder, whereupon the motor will be adapted for repulsion operation, as before. It is apparent that our 85 short-circuiting device is reliable and effective in operation for, since the contact fingers are formed from a single plate of conducting material, there are no parts to get out of order or to require inspection, as in 90 the case of short-circuiting devices having pivotally mounted contact fingers.

A modification in the form of the contact plate is shown in Fig. 7 wherein a flexible disk 36 is mounted on the plate 9. The disk 95 36 is provided with an offset portion 37, similar in form to the fingers 33 of the plate 31. A second disk 38 of smaller diameter is located intermediate the disk 36 and the plate 9, the disk 38 being preferably formed 100 of material possessing considerable rigidity in order to reinforce the contact disk 36. A further modification is shown in Fig. 8 wherein a stiff disk 39 is formed with an offset portion 40 having a machined face 41 105 parallel to the plate 9.

While we have shown and described our invention in its preferred forms, it is not so limited but is susceptible of various other minor changes and modifications within the 110 scope of the appended claims.

We claim as our invention:

1. In an electric motor embodying a rotatable commutator member, a short-circuiting device comprising a relatively movable contact member and means for causing both axial and rotative movement of said contact member relative to said commutator member.

2. In an electric motor embodying a rotatable commutator member and a shaft therefor, a short-circuiting device comprising a contact member loosely mounted on said shaft and means for causing combined axial and rotative movement of said contact member relative to said commutator member.

3. A short-circuiting device for electrical apparatus comprising a rotatable shaft, a contact plate movably mounted thereon,

means responsive to variations in the speed of said shaft for causing rotative movement of said plate with respect thereto and means coacting with said shaft for causing simultaneous axial movement of said plate.

4. In a dynamo-electric machine, the combination with a rotatable shaft having a commutator cylinder comprising a plurality of spaced conducting bars, a contact member movably mounted upon said shaft, and means for moving said contact member in a helical path for engagement with the ends of said bars.

5. A short-circuiting device for electrical apparatus comprising a rotatable shaft, a contact plate movably mounted thereon, centrifugally actuated members for causing rotative movement of said plate with respect thereto, and a slot-and-pin connection between said shaft and said plate for causing axial movement of said plate.

6. In a dynamo-electric machine, the combination with a rotatable shaft having an armature and an associated commutator cylinder mounted thereon, and a short-circuiting device for said commutator cylinder comprising a contact plate having portions thereof inclined to the axis of said shaft, of means for causing a combined rotative and axial movement of said plate with respect to said commutator cylinder.

7. The combination with an armature of an alternating-current motor provided with a commutator, of an automatic controlling device therefor comprising two opposing members, one of said members being fixedly mounted on the motor shaft, a short-circuiting ring carried by one of said members adjacent the commutator, centrifugally acting means causing relative rotative movement

of said members, means causing a relative axial movement of said members under the influence of said relative rotative movement to bring the short-circuit-ring in contact with the commutator, and means opposing the relative rotative and axial movements of said members.

8. The combination with the armature of an alternating-current motor provided with a commutator, of an automatic controlling device therefor comprising a member fixedly mounted on the motor shaft, a disk movably mounted on the shaft and interposed between said member and the commutator, a short-circuiting ring carried by said disk adjacent the commutator, centrifugally acting means causing relative rotative movement of said member and disk, means causing relative axial movement thereof under the influence of said relative rotative movement to bring the short-circuiting ring in contact with the commutator, and means opposing the relative rotative and axial movements of said member and disk.

9. A short-circuiting device for electrical apparatus comprising a rotatable shaft, a contact plate movably mounted thereon and capable of simultaneous rotative and axial movement with respect thereto, means responsive to variations in the speed of said shaft for causing rotative movement of said plate, and means whereby the axial movement is dependent on the degree of rotative movement.

In testimony whereof, we have hereunto subscribed our names this 28th day of April, 1916.

GEORGE H. GARCELON.
JOSEPH L. CHANTEMERLE.
